UNITED STATES PATENT OFFICE.

STEPHEN S. JOHNSON, OF SOUTH ORANGE, NEW JERSEY.

MATTING DEVICE.

1,277,318.

Specification of Letters Patent. Patented Aug. 27, 1918.

Application filed January 20, 1915. Serial No. 3,423.

To all whom it may concern:

Be it known that I, STEPHEN S. JOHNSON, a citizen of the United States of America, and residing at South Orange, in the county 5 of Essex and State of New Jersey, have invented a certain new and Improved Matting Device, of which the following is a specification.

My invention relates to a matting device 10 and particularly to means for readily determining the desired field for the matted picture and for facilitating the cutting of the mat to such field.

In the accompanying drawings,

15 Figure 1 is a perspective of a matting frame in which my invention is embodied in one form;

Fig. 2 is a perspective of a coöperating cutting block;

20 Figs. 3 and 4 are cross sections through the apparatus; and

Fig. 5 is a plan of a cut mat.

As is well known to those engaged in the art of preparing lantern slides, the usual 25 slide plate includes a greater or less marginal area which it is undesirable to include within the exposure field of the finished slide as the latter is to be thrown upon the screen. The portions of the view area which 30 it is desired to block out by means of a mat, may be merely superfluous or undesirable from an artistic standpoint, or for the reason that attention is desired to be directed to a particular feature of the view. 35 The usual method followed in the preparation of the blocking out mat is to employ a mat of standard type which is of the same size as the lantern slide, is opaque on one face and white on the other, the latter being furnished with a series of intersecting 40 lines to guide the operator in the cutting of the mat. The operator ordinarily places the slide over the mat and marks on the margins of the latter the lines on which he thinks the mat should be cut in order to give 45 the desired exposure field for the slide. This is little better than guess work and it is not an uncommon occurrence to cut three or four mats for a single slide before 50 the desired field is attained.

Two-part mats have also been used, each part comprising sections at right angles to each other which coöperate with the similar sections of a like part to afford an open 55 field which may be varied by manipulating the coöperating parts upon the slide until

the desired exposure field has been determined. This facilitates the determination of the field but it is extremely difficult then to secure the coöperating parts in their 60 proper position upon the slide, since each part must be separately cut and readjusted to position upon the slide.

To obviate these difficulties I have now devised a matting frame which in the form 65 here shown comprises a light wooden body 10, centrally apertured to afford a seat 11 for the lantern slide 12. The seat 11 may be made with exactness to the standard lantern slide size so that the latter fits snugly 70 therein and is thus supported without auxiliary means for engaging the same; or if desired, means may be provided to hold the slide in position during the location of its exposure field as hereinafter described. 75 Pivoted spring clips 13 may be employed for this purpose, engaging the slide at its margins. The frame 10 is peripherally slotted at 14 on its four sides to receive the four flat shutters 15 which pass through 80 the slots with their inner edges projecting in overlapped position into the area in front of the slide resting in its seat 11. The slots 14 are so located that the shutters pass closely adjacent to one face of the slide 12, 85 and they may be moved back and forth across the face of the latter to expose a larger or smaller field 16 of that particular rectangular shape which best suits the slide in hand. The shutters are so guided that 90 the field 16 is maintained rigidly rectangular in accordance with the requirements of preferred practice for lantern slide mats. Any suitable device may be provided for 95 frictionally engaging the shutters 15 to hold the same in their adjusted positions. I have here shown merely leaf springs 17 arranged in the slots 14 and bearing against the surfaces of the shutters.

The manner in which the guide slots 14 100 for the shutters 15 are formed is immaterial. In the present construction this is accomplished by rabbetting one face of the body 10 to form the guideways and then covering this face with the thin facing 25 which is apertured in register with the seat 11 for the slide plate. The margins 26 of facing 25 may project slightly beyond the edges of the seat to form a stop in case the slide plate is accidentally forced through the seat 11. 110 When the shutters 15 project into the area of the seat, as they ordinarily do, they form

a stop and the projecting margins 26 of the facing are unnecessary. The leaf springs 17 which frictionally engage the shutters 15 may conveniently be mounted on the inner face of the facing 25.

Coöperating with the main frame 10 I provide a cutting block 18 adapted to fit snugly in the seat 11 of the frame 10 and preferably provided upon its face with a sheet of brass 19 or the like to form a suitable ground for the cutting knife. Wings 20 extending outward from the cutting block engage the shoulders 21 of the frame and aid in supporting the block at the aperture 11. Guides 22 at two adjacent sides of the block afford a right angular abutment against which the mat 23 to be cut is accurately positioned upon the block to register with the slide seat 11.

20 The manner in which the device is used is readily understood. The operator first positions a slide in the seat 11 in the frame 10. He thereupon adjusts the several shutters 15 across the face of the slide to determine 25 the exact exposure field 16 for the latter. After this field has been determined, the slide is removed and the cutting block 18, with the mat blank 23 in position thereon, is placed in the seat 11 and the mat cut along 30 the edges of the shutters 15. It is obvious that upon the removal of the cut mat from the block 18, the exact field 16 which the operator desired, has been cut from the mat and the latter may be at once adjusted upon 35 and secured to the slide in well known manner.

Obviously if it is not desired to cut the mat on the block 18, it may be marked with a pencil which in this event would be guided 40 along the edge of the shutters 15 to indicate the field 16 upon the mat blank. The latter would then be removed from the block 18 to a cutting board or the like and cut out along the marked lines.

45 One obvious advantage of the present device is that the use of ruled mats is entirely unnecessary. Any opaque paper of proper size may be placed upon the cutting block and cut or marked in accordance with the field 16 outlined by the shutters. The old uncertain practice of guessing at the field or measuring it out by rule is entirely replaced by the present much speedier and certain operation of adjusting the shutters directly 50 with relation to the slide to obtain the desired artistic effect, and then cutting or marking the mat blank directly from the field so outlined by the shutters.

60 A further feature of value may be noted. The frame 10 may be recessed at 24 to accommodate a ground glass diffuser adjacent the slide. If the frame 10 be made of a size to fit the inclined support of a retouching stand, as I prefer that it should be made, it 65 may be now conveniently used for holding

the slide for retouching or coloring in which case the shutters 15 would be employed to confine the light to the particular portion of the slide on which the work is being done. Of course during such use, the cutting block 70 18 is removed from position.

The invention has been described with special relation to the cutting of mats for standard size lantern slides. Obviously it may be employed however for matting pictures, or plates of any size if the frame and cutting block are made of suitable size or adjustable to various sizes. The precise construction of the frame shown may be variously modified to give added strength or 75 lightness or to improve the means for holding the plate, cutting block etc. without departing from what I claim as my invention.

I claim as my invention:—

1. A matting device of the character described, comprising an apertured frame having means for temporarily supporting an image bearer at the frame aperture, shutters adjustable across the frame aperture to determine the desired exposure field of the image, in combination with a carrier for a mat blank adapted to support the latter in juxtaposition to said shutters after the removal of the image bearer and in a position substantially in register with that occupied 95 by the image bearer while in the frame, for the purpose described.

2. A matting device of the character described, comprising an apertured frame with seat for temporarily supporting an image 100 bearer at the frame aperture, shutters adjustable across the frame aperture and adjacent the said seat, in combination with a carrier for a mat blank adapted to support the latter in juxtaposition to said shutters after the removal of the image bearer and in a position substantially in register with that occupied by the image bearer while seated in the frame, for the purpose described.

3. A matting device of the character described, comprising a frame centrally apertured and having a seat surrounding said aperture to receive an image bearer to be matted, said frame being also slotted to afford marginal passageways opening to said central aperture adjacent said seat, and shutters moving in said passageways and adjustable across said aperture to determine the desired exposure field for the image, in 115 combination with a carrier for the mat blank adapted to support the latter in juxtaposition to said shutters after the removal of the image bearer and in a position substantially in register with that occupied by 120 the image bearer while seated in the frame, for the purpose described.

4. A matting device of the character described, comprising an apertured frame having a seat for temporarily supporting an 130

image bearer at the frame aperture, and shutters adjustable across said frame aperture to determine the desired exposure field for the image, in combination with a cutting block adapted to carry a mat blank and placeable in the said seat after the removal of the image bearer.

5. A matting device of the character described, comprising an apertured frame having a seat for temporarily supporting an image bearer at the frame aperture, and shutters adjustable across said frame aperture to determine the desired exposure field for the image, in combination with a cutting block adapted to carry a mat blank and placeable in the said seat after the removal of the image bearer, together with a metallic cutting face on said block.

6. A matting device of the character described, comprising an apertured frame having a seat for supporting an image bearer at the frame aperture, and a surrounding seat for a sheet of ground glass, and shutters adjustable across the frame aperture

adjacent the seat for the image bearer but 25 on the side thereof opposite that for the ground glass.

7. A matting device of the character described, comprising an apertured frame having means for temporarily supporting an 30 image bearer at the frame aperture, and shutters slideable across said aperture to determine the desired field of display of said image, in combination with a carrier for a mat blank having means for detachably supporting the mat blank thereon and adapted, after the removal of the image bearer, to hold the said mat blank in juxtaposition to the shutters and in a position substantially 35 in register with that occupied by the image 40 bearer while in the frame.

In testimony whereof I have signed my name to this specification, in the presence of two subscribing witnesses.
